MOVING STAIRWAY HANDRAIL DRIVE

David Leonard Lindquist, White Plains, and Arthur Edward Handy, Lynbrook, N. Y., assignors to Otis Elevator Company, New York, N. Y., a corporation of New Jersey

Application June 10, 1939, Serial No. 278,580

11 Claims. (Cl. 198—16)

The invention relates to handrails of moving stairways and especially to the driving of the handrails.

Moving stairways are provided with moving handrails for the convenience of persons using the stairways. Two handrails are provided, one on each side of the stairs, and are arranged to be driven in synchronism with the steps. It has been the practice for a great many years to provide a traction drive for the handrails. In these arrangements, the handrail passes around newel wheels at the ends of the stairway. At one end of the stairway, usually the upper end, the handrail also passes around tensioning wheels positioned between the newel wheel at that end of the stairway and the lower run of the handrail. This newel wheel is driven and at least one of the tensioning wheels also is driven to provide sufficient traction for driving the handrail. These driving wheels are driven from the stairway driving motor to rotate at the same peripheral speed.

On both the upper run and the return run of the incline, each handrail slides on guides extending inside the handrail. These guides have curved portions near the ends of the stairway. There is considerable friction between the handrail and its guides at these points. Also, friction exists between the guides and the handrail on the inclines which may be considerable in case of high rise stairways. Due to this friction a considerable force is required to drive the handrail and hence a considerable tension must be maintained in the handrail. As the handrail passes around each driven sheave the tension is greater at the point where the handrail engages the sheave than it is at the point at which it leaves the sheave. Furthermore, the difference in tension in the handrail for one of these wheels is greater than the difference in tension in the handrail for the other wheel. The wheel for which the greatest difference in tension exists is dependent upon the direction of movement of the stairway. Due to this difference in tension in the handrail creepage takes place on each wheel and this creepage is different on the two wheels due to the fact that the difference in tension is not the same for both of them. In order to compensate for this difference in creepage, slippage of the handrail occurs and this takes place in a series of jumps.

It is the object of the invention to cause smooth operation of the handrail whether applied to a one-way or reversible stairway.

The invention involves driving at least two of the wheels about which the handrail passes in such way as to permit relative rotative movement of the wheels with respect to each other, applying torque to the respective wheels in an amount

to obviate any slippage of the handrail due to any inequality of creepage of the handrail on said wheels. Although the invention may be carried out by various means, an arrangement will be described in which the upper newel wheel is driven from the stairway driving motor and in which a tensioning wheel is driven by an auxiliary motor separate from the stairway driving motor. In carrying out the invention with such arrangement as applied to a reversible stairway, the auxiliary motor is controlled in such way as to provide the proper torque for both descending and ascending operations of the stairway. Such arrangement will be described.

Features and advantages of the invention will be apparent from the following description and appended claims.

In the drawings:

Figure 1 is a diagrammatic representation in side elevation of a moving stairway embodying the invention;

Figure 2 is a simplified wiring diagram of a control system for the stairway illustrated in Figure 1; and

Figure 2a is a key sheet for Figure 2 showing the electromagnetic switches in spindle form with the contacts and coils arranged on the spindles in horizontal alignment with the corresponding contacts and coils in the wiring diagram.

Referring to Figure 1, the moving stairway extends between a lower landing 10 and an upper landing 11. In the arrangement illustrated, the stairway comprises an endless series of steps 12 driven at the upper end of the stairway by means of sprocket wheels through running gear chains (not shown). These sprocket wheels are mounted on and driven by the main drive shaft 13 of the stairway. This drive shaft in turn is driven by an electric motor 14 through reduction gearing 15, sprocket wheel 16, driving chain 17 and sprocket wheel 18 secured to shaft 13.

The stairway has two endless moving handrails, one on each side thereof, the handrail 20 for one side being illustrated. This handrail extends around newel wheels 21 and 22 at the ends of the stairway. On its upper and lower runs the handrail is guided by elongated guide members extending inside the handrail. Between the newel wheel 32 at the upper end of the stairway and the lower run the handrail passes around tensioning wheels 23 and 24.

In the arrangement illustrated, wheel 24 is a driven wheel and is mounted on a shaft 25 having a fixed support, while wheel 23 serves as the tightener wheel and is mounted on a shaft 26 supported by a sliding carriage 19. Carriage 19 is connected by means of a cable 27 passing over an idler pulley 28 to a tensioning weight 30.

to maintain the handrail taut. Another cable 31 is connected to the top of tensioning weight 30 and extends through a flexible guide tube 32 to a safety device 33. This safety device comprises a pair of limit switches 34 and 35. Each of these switches is biased to open position but is normally maintained closed by means of a latch 36. This latch is operable by cam 37 adjustably mounted on a lift rod 38 and having a 10 pulley 29 at the upper end thereof. The cable 31 from the tensioning weight 30 passes around this pulley on the left hand lift rod and then up to a fixed support. Thus, upon stretch of the handrail a predetermined amount or the 15 breaking of the handrail, the rod is lifted to a point where the lower portion of cam 37 trips the latch 36 to open switch 34. Also should the tensioning weight 30 be raised as, for example, by some one trying to lift the handrail off its 20 guide, the lift rod is lowered into position where the upper portion of cam 37 engages and trips the latch to open the switch. The handrail for the other side of the stairway is tensioned in a similar manner, the operating cable 39 for switch 35 for that side of the stairway being connected to a similar tensioning weight on the opposite side of the stairway.

The upper newel wheel 22 for the handrail is driven from the main drive shaft 13 through a 30 sprocket wheel 40 secured to the main drive shaft, sprocket chain 41 and sprocket wheel 42 secured to drive shaft 43 for newel wheel 22. The upper newel wheel for the opposite side of the stairway is driven in a similar manner from a sprocket 35 wheel on shaft 13. The tensioning wheel 24 is driven by a motor 44 separate from the main driving motor 14. The drive shaft 25 for this wheel is provided with a sprocket wheel 45 which is driven by motor 44 through reduction gearing 46, sprocket wheel 47, sprocket chain 48, sprocket 40 wheel 50 on countershaft 51, a second sprocket wheel 52 on countershaft 51, and sprocket chain 53. The tensioning wheel 24 for the opposite side of the stairway is driven in a similar manner from a sprocket wheel on countershaft 51.

Referring now to Figure 2, the control system illustrated is for a three-phase alternating current source of power with motors 14 and 44 three-phase squirrel cage induction motors. It will be understood, however, that the invention is applicable to other sources of power supply and other types of driving motors. The rotor of the main driving motor 14 is designated 60, while the stator windings of this motor are designated 61, 62 and 63. The rotor of the auxiliary motor 44 is designated 65, while the stator windings of the auxiliary motor are designated 66, 67 and 68. 70, 71 and 72 are torque adjusting resistances for motor 44. 73 is a triple pole main line switch for connecting in the supply mains 74, 75 and 76. The feed lines 77 and 78 for certain of the control circuits are illustrated as separate lines but it is to be understood that these lines may be fed directly or indirectly from the supply mains. 80 65 and 81 are key operated starting switches for the moving stairway, these switches being arranged preferably one at the upper landing and the other at the lower landing of the stairway. 82 is an electromagnetic release coil for the machine pawl brake 83. When the pawl brake is lifted, it separates contacts 84 and engages contacts 85 in the control circuits. 86 is a rectifier for supplying current derived from supply lines 77 and 78 to coil 82. This rectifier is feed from the transformer 87. The machine governor is

provided with contacts 88 which close when the machine attains a certain speed, say 80% of full speed. This governor is also provided with contacts 90 which separate when a predetermined overspeed occurs. 91 and 92 are stop buttons located preferably one at the lower landing and one at the upper landing of the stairway. These buttons are arranged in a control circuit common to certain of the operating switches of the stairway, and upon the pressing of either, this circuit is opened to bring the stairway to a stop. Also arranged in this circuit are the broken handrail switches 34 and 35, previously described, broken chain switches 93 and 94, fire door contacts 95 and service switch 96. Also arranged in this circuit are contacts of overload and reverse phase relays which will be referred to later.

The electromagnetic switches have been designated as follows:

B	Brake switch	20
BB	Brake relay	
BD	Down button relay	
BU	Up button relay	
D	Delta switch	25
DD	Delta relay	
DR	Direction relay	
DS	Down direction switch	
DT	Time relay	
HD	Handrail down direction switch	30
HOA	Handrail overload relay	
HOB	Handrail overload relay	
HU	Handrail up direction switch	
OA	Overload relay	
OB	Overload relay	35
R	Reverse phase relay	
US	Up direction switch	
Y	Star switch	

Throughout the description which follows these letters, in addition to reference numerals, will be applied to parts of the above designated switches. The electromagnetic switches are illustrated in deenergized positions. Contacts R1 of the reverse phase relay, OA1 and OB1 of the overload relays and HOA1 and HOB1 of the handrail overload relays are arranged in the circuit with the safety devices and the stop buttons. Thus, upon occurrence of reverse phase or single phase, or overload on either motor 14 or motor 44, the common control circuit is broken to cause the stopping of the stairway.

The circuits are shown in "straight line" form, that is, in which circuits are as direct as possible to render them easy to follow. With such diagram, the coils and contacts of the electromagnetic switches are separated. The relationship of these coils and contacts may be seen from Figure 2a where the switches are arranged in alphabetical order and are shown in spindle form. The coils and contacts are positioned on the spindles in horizontal alignment with the corresponding elements of the wiring diagram. Thus by first locating any coil or contact on the spindle diagram the corresponding element on the corresponding wiring diagram may be found.

Assume that it is desired to start the stairway for ascending travel. One of the key operated switches, say switch 80, is turned clockwise, completing a circuit for the coil of up button relay BU. This relay operates to engage contacts BU1 and BU2. The engagement of contacts BU2 completes a circuit for the coil of up direction switch US, while the engagement of both contacts BU2 and BU1 completes a circuit for the coil of brake switch B, the latter circuit extending from the 75

left hand feed line 77 through contacts BU2 and BU1 in the order named. The up direction switch US upon operation separates interlock contacts US3 and US5 in the circuits for the coil of down direction switch DS and the coil of handrail down direction switch HD respectively. It engages contacts US1 and US2 to prepare holding circuits for the coils of switches US and B. It also engages contacts US4, completing a circuit 5 for the coil of handrail up direction switch HU. It also engages contacts US6 and US7 in the circuits for the stator windings of driving motor 14, the engagement of contacts US6 connecting the coil of star switch Y across the supply mains 15 and 16.

Star switch Y and handrail up direction switch HU operate simultaneously. Switch Y separates interlock contacts Y1 in the circuit for the coil of delta switch D. It also engages contacts Y2 and Y3 connecting the stator windings of motor 14 in star relation to the supply mains, the direction of rotation of the rotating field being established by contacts US6 and US7 for ascending operation of the stairway. Switch HU separates interlock contacts HU1 in the circuit for the coil of handrail down direction switch HD. It also engages contacts HU2, HU4, HU5 and HU7, connecting the stator windings of motor 44 to the supply mains in star relation. Contacts HU5 20 and HU7 establish the star connection while contacts HU2 and HU4 establish a direction of rotation of the rotating field of motor 44 to cause rotation of the motor for ascending movement of the handrails. Brake switch B operates at 25 the same time as switches US, HU and Y to engage contacts B1 and complete the circuit for the primary winding of transformer 87, causing the energization of the release electromagnet 82 of the pawl brake. Thus as the motors 14 and 44 are energized, the pawl brake is released, permitting starting of the stairway in ascending operation.

The pawl, upon being released, separates contacts 84 to insert cooling resistance 97 in circuit 30 with the primary winding of transformer 87 and engages contacts 85 to complete a circuit for the coil of brake relay BB. This relay, upon operation, engages contacts BB1 further to prepare holding circuits for the coils of switches B and US. It also separates contacts BB2 and engages contacts BB3, the separation of contacts BB2 preventing the establishment of a circuit through contacts BU2 for the coil of direction relay DR. Relay BB also engages contacts BB4 to prepare 35 a circuit for the coil of delta switch D.

Upon the speed of the motor attaining a certain value, governor switch contacts 88 close and complete a circuit for the coil of time relay DT. Upon the expiration of a certain time interval, relay DT operates to engage its contacts DT1. This completes a circuit for the coil of delta relay DD. Relay DD separates contacts DD2 to deenergize the coil of star switch Y and engages contacts DD1 further to prepare the circuit for the coil of delta switch D. Star switch Y upon dropping out separates contacts Y2 and Y3 and engages contacts Y1. Contacts Y1 connect the coil of delta switch D across supply mains 75 and 76. This switch operates to engage contacts D4, D5 and D6 to connect the stator windings of driving motor 14 in delta relation for a full speed running of the stairway in the ascending direction. Switch D also separates interlock contacts D2 and D3 in the circuits for 40 the coils of direction relay DR and star switch Y 45

respectively, contacts D2 being provided to prevent energization of the coil of relay DR under conditions where a starting switch is operated to operate down button relay BD after the change of the connections in the stator windings of main driving motor 14 from star to delta has been effected in starting the stairway in ascending operation. It also engages contacts D1, which completes the holding circuits through contacts US1 for the coils of switches B and US, permitting the return of key operated starting switch 50 55 to neutral position, where the key may be withdrawn.

To start the stairway from rest for descending travel, one of the key operated starting switches, say switch 80, is operated counterclockwise to complete the circuit for the coil of down button relay BD. This relay operates to engage contacts BD1 and BD2 to complete a circuit for the coil of brake relay B. The engagement of contacts BD1 also completes a circuit through contacts BB2 for the coil of up direction switch US. Switches B and US operate as previously described to cause the release of the pawl brake and the connection of the stator windings of motors 14 and 44 in star relation to the supply mains for ascending travel of the stairway. This operation is only momentary, however, for the brake relay BB, which operates as a result of the release of the pawl brake and consequent engagement of contacts 85, completes a circuit by the engagement of contacts BB3 for the coil of direction relay DR. Relay DR upon operation separates contacts DR1 to break the circuit for the coil of up direction switch US, breaking the circuit for the stator windings of main driving motor 14 and also the circuit for auxiliary motor 44 by causing the dropping out of handrail up direction switch HU. Switch US engages its interlock contacts US3, completing a circuit for the coil of down direction switch DS. Switch DS engages its contacts DS7 and DS8. The engagement of contacts DS7 connects the coil of star switch Y across supply mains 74 and 75, causing reoperation of this switch to reconnect the stator windings of the main driving motor in star relation. However, owing to the fact that contacts DS7 and DS8 are closed instead of US6 and US7, the direction of rotation of the rotating field of the main driving motor is such as to 50 cause rotation of the driving motor for descending travel of the stairway. At the same time, contacts DS8 engage to complete the circuit for the coil of handrail down direction switch HD, contacts US5 being engaged as a result of the dropping out of switch US. Switch HD operates to engage contacts HD3, HD5, HD6, HD8 and HD9, connecting the stator windings of auxiliary motor 44 to the supply mains in delta relation. Contacts HD3, HD5 and HD9 establish the 55 delta connection while contacts HD6 and HD8 establish a direction of rotation of the rotating field of motor 44 to cause rotation of the motor for descending movement of the handrails. The purpose of momentarily starting the stairway in 60 ascending travel when it is desired to have the stairway operate in the descending direction is to effect the release of the pawl brake, the brake switch B being maintained energized through contacts BD1 and BD2 when the change of connections is effected to reverse the direction of travel.

Incident to the starting of the stairway for descending travel, handrail down direction switch HD separates interlock contacts HD1 in 75

the circuit for the coil of handrail up direction switch HU and down direction switch DS separates interlock contacts DS3 and DS5 in the circuits for the coils of switches US and HU respectively. Switch DS also engages contacts DS2 and DS4 to prepare self-holding circuits for the coils of switches B and DS. Also, it separates contacts DS1 in the circuit for the coils of DD and DT, preventing the operation of these switches during descending travel of the stairway and thus preventing the dropping out of switch Y and the operation of switch D to change the connections for the stator windings of the main driving motor 14 from star to delta relation. Upon the speed of the stairway attaining the value for which governor switch contacts 88 are set, these contacts close, completing holding circuits for the coils of switches B, DR and DS. Thus the key operated switch may be returned to neutral and the key withdrawn.

When the stairway is operating as a descending one, the difference between the tension in each handrail at the point where it runs on wheel 24 and the tension at the point where it runs off this wheel is greater than when the stairway is operating as an ascending one. An auxiliary motor is employed of sufficient power to be capable of providing correct torque to drive these wheels under such conditions (in the arrangement illustrated with the motor delta connected). Also, the gearing between the motor and wheels 24 is such as to cause the motor to run at a certain percentage, say 80%, of synchronous speed to insure sufficient torque being applied under operating conditions. When the stairway is operating as an ascending one, the greatest difference in tension in the handrails is at the points where the handrails run onto and off the upper newel wheels while the difference in tension of the handrails at the points where they run onto and off the wheels 24 is relatively small. The auxiliary motor 44 under these conditions may operate star connected as previously described as it is capable of providing sufficient torque thus connected to drive wheels 24 during ascending operation. The torque of motor 44 may be further adjusted if desired by means of resistances 70, 71 and 72, contacts HU3, HU6 and HU8 connecting adjusted portions of these resistances in circuit with the motor during ascending operation and contacts HD2, HD4 and HD7 connecting adjusted portions of these resistances in circuit with the motor during descending operation. With the wheels 24 driven by a motor separate from the main driving motor, as in the arrangement above described, there is no slippage of the handrails due to a difference in creepage on wheels 24 with respect to that on the newel wheels 22, for the motor 44 acts automatically to drive wheels 24 at a speed which compensates for the difference in creepage. This is true regardless of whether the stairway is a one-way stairway, i. e., either ascending or descending, or a reversible stairway. Also, with slippage eliminated, the surfaces of the driven wheels 22 and 24 on each side of the stairway may be of a material, such as rubber, to increase the traction between the handrails and their driven wheels without any undesirable effects. Such construction might be desirable, especially in the case of high rise stairways.

Although an arrangement has been described as applied to alternating current motors, other motors including direct current motors may be used. When direct current motors are employed the torque of the auxiliary motor may be con-

trolled if desired as by controlling the strength of a series field winding provided for the motor. Tensioning wheel 23 may be driven instead of wheel 24 or both these wheels may be driven. The weights 30 may be connected to wheels 24 and wheels 23 driven. Also, a separate auxiliary motor may be provided for driving the tensioning wheel or wheels on each side of the stairway. Still other arrangements may be provided for permitting relative rotative movement of the driven wheels for a handrail. Also, other forms of control systems may be provided and the invention may be applied to other forms of moving stairway construction.

Therefore, as many apparently widely different embodiments of this invention may be made without departing from the scope thereof, it is intended that all matter contained in the above description or shown in the accompanying drawings shall be interpreted as illustrative and not in a limiting sense.

What is claimed is:

1. A moving stairway comprising; a newel wheel; an additional wheel; an endless handrail passing in traction relation around said newel wheel and said additional wheel; driving means for said newel wheel; and driving means for applying torque to said additional wheel and for driving said additional wheel at a speed which varies to compensate for any difference in creepage of said handrail on said newel wheel and said additional wheel.

2. A moving stairway comprising; an endless handrail; a plurality of wheels around which said handrail passes in traction relation; a motor for driving one of said wheels; and an additional motor for driving another of said wheels.

3. A moving stairway comprising; a series of steps; an endless handrail; a plurality of wheels around which said handrail passes in traction relation; a motor for driving the stairway; means connecting one of said wheels to said motor to be driven thereby; an auxiliary motor; and means connecting another of said wheels to said auxiliary motor to be driven thereby.

4. A moving stairway comprising; a series of steps; a newel wheel at each end of the stairway; an additional wheel; an endless handrail passing in traction relation around the newel wheels at the ends of the stairway and around said additional wheel; a motor for driving the stairway; means connecting said upper newel wheel to said motor to be driven thereby to drive said handrail in synchronism with said steps; an auxiliary motor; and means connecting said additional wheel to said auxiliary motor to be driven thereby to assist said upper newel wheel in driving said handrail.

5. A moving stairway comprising; a series of steps; a newel wheel at the upper end of the stairway; a newel wheel at the lower end of the stairway; a pair of tensioning wheels at the upper end of the stairway; an endless handrail passing in traction relation around the newel wheels at the ends of the stairway and the tensioning wheels between the upper newel wheel and the lower run of the handrail; means associated with one of said tensioning wheels for maintaining said handrail taut; a motor for driving the stairway; means operable by said motor for driving said newel wheel at the upper end of the stairway partially to drive said handrail; an auxiliary motor; and means operable by said auxiliary motor for driving the other of

said tensioning wheels to assist in driving said handrail.

6. A moving stairway comprising; a series of steps; a newel wheel at each end of the stairway; an additional wheel; an endless handrail passing in traction relation around the newel wheels at the ends of the stairway and around said additional wheel; means for driving the stairway; means for driving said upper newel wheel and said additional wheel to drive said handrail in synchronism with said steps, said last named means including means permitting relative rotative movement of such wheels; and means for controlling the direction of rotation of all of said driving means to cause either ascending or descending operation of said steps and handrail.

7. A moving stairway comprising; a series of steps; a newel wheel at each end of the stairway; an additional wheel; an endless handrail passing in traction relation around the newel wheels at the ends of the stairway and around said additional wheel; a motor for driving the stairway; means connecting the upper newel wheel to said motor to be driven thereby; an auxiliary motor; means connecting said additional wheel to said auxiliary motor to be driven thereby; and means for controlling the direction of rotation of said motors to cause either ascending or descending operation of said steps and handrail.

8. A moving stairway comprising; a series of steps; a newel wheel at the upper end of the stairway; a newel wheel at the lower end of the stairway; an endless handrail passing in traction relation around the newel wheels at the ends of the stairway; means for maintaining said handrail taut, said means including an additional wheel around which said handrail passes in traction relation between the upper newel wheel and the lower run of the handrail; a motor for driving the stairway; means for controlling the direction of rotation of said motor to cause either ascending or descending operation of said stairway; means operable by said motor for driving said newel wheel at the upper end of the stairway partially to drive said handrail; an auxiliary motor; means operable by said auxiliary motor for driving said additional wheel to assist in driving said handrail; and means controlled by said direction controlling means for causing operation of said additional wheel by said auxiliary motor to drive said handrail in the same direction as said upper newel wheel.

9. A moving stairway comprising; a series of steps; a newel wheel at the upper end of the stairway; a newel wheel at the lower end of the stairway; a pair of tensioning wheels at the upper end of the stairway; an endless handrail passing in traction relation around the newel wheels at the ends of the stairway and the tensioning wheels between the upper newel wheel and its lower run; means associated with one of said tensioning wheels for maintaining said handrail taut; a motor for driving the stairway; means for controlling the direction of rotation of said motor to cause either ascending or descending operation of said stairway; means operable by said motor for driving said newel wheel at the upper end of the stairway partially to drive said handrail; an auxiliary motor; means operable by said auxiliary motor for driving the other of said tensioning wheels to assist in driving

said handrail; and means for controlling the direction of rotation of said auxiliary motor to cause said other tensioning wheel to drive said handrail in the same direction as said upper newel wheel.

10. A moving stairway comprising; a series of steps; a newel wheel at the upper end of the stairway; a newel wheel at the lower end of the stairway; a pair of tensioning wheels at the upper end of the stairway between the newel wheels; an endless handrail passing in traction relation around the newel wheels at the ends of the stairway and also around the tensioning wheels between the upper newel wheel and the lower run of the handrail; means associated with one of said tensioning wheels for maintaining said handrail taut; a motor for driving the stairway; means for controlling the direction of rotation of said motor to cause either ascending or descending operation of said stairway; means operable by said motor for driving said newel wheel at the upper end of the stairway; an auxiliary motor; means operable by said auxiliary motor for driving the other of said tensioning wheels; means controlled by said direction controlling means for controlling the direction of rotation of said auxiliary motor to cause said other tensioning wheel to drive said handrail in the same direction as said newel wheel at the upper end of the stairway, said auxiliary motor applying a certain torque to said other tensioning wheel when the stairway is descending; means for decreasing the torque which said auxiliary motor applies to said other tensioning wheel when the stairway is ascending; and additional means for adjusting the torque of said auxiliary motor for either descending or ascending operation of the stairway.

11. A moving stairway comprising; a series of steps; a newel wheel at the upper end of the stairway; a newel wheel at the lower end of the stairway; a pair of tensioning wheels at the upper end of the stairway between the newel wheels; an endless handrail passing in traction relation around the newel wheels at the ends of the stairway and also around the tensioning wheels between the upper newel wheel and the lower run of the handrail; means associated with one of said tensioning wheels for maintaining said handrail taut; a polyphase induction motor for driving the stairway; means for controlling the direction of rotation of said motor to cause either ascending or descending operation of said stairway; means operable by said motor for driving said newel wheel at the upper end of the stairway partially to drive said handrail; an auxiliary polyphase induction motor; means operable by said auxiliary motor for driving the other of said tensioning wheels to assist in driving the handrail; means controlled by said direction controlling means for controlling the direction of rotation of said auxiliary motor to cause said other tensioning wheel to drive said handrail in the same direction as said newel wheel at the upper end of the stairway; means for causing the stator windings of said auxiliary motor to be connected in delta relation when the stairway is descending and in star relation when the stairway is ascending; and a source of polyphase alternating current for said motors.
